121,918

DESIGN FOR A TRANSPARENT SUPPORT
FOR A CONTAINER OR SIMILAR ARTI-CLE

Félicie Eugénie Amélie Wanpouille Bergaud,
Paris, France

Application May 4, 1940, Serial No. 92,168

Term of patent 7 years

To all whom it may concern:

Be it known that I, Félicie Eugénie Amélie Wanpouille Bergaud, a citizen of the French Republic, residing at Paris, France, have invented a new, original, and ornamental Design for a Transparent Support for a Container or Similar Article, of which the following is a specification, reference being had to the accompanying drawing, forming part thereof.

for a container or similar article showing my new design: Figure 2 is a front view thereof; Figure 3 is a side view thereof; Figure 4 is a rear view thereof.

I claim:

The ornamental design for a transparent support for a container or similar article, substantially as shown.

FÉLICIE EUGÉNIE AMÉLIE
WANPOUILLE BERGAUD.
